LIQUID REFRIGERATING AND DISPENSING SYSTEM

Joseph Askin, Buffalo, N. Y., assignor to Fedders Manufacturing Company, Inc., Buffalo, N. Y.

Application April 1, 1933. Serial No. 663,970

8 Claims. (Cl. 62—141)

This invention relates to a liquid refrigerating and dispensing system, and it has particular reference to apparatus for cooling a flowing stream of liquid and concurrently applying to such liquid sufficient pressure to cause the liquid to flow.

According to the present invention, means are provided for dispensing a beverage which is located at a lower point than the dispensing faucet, and simultaneously applying to such beverage a refrigerating or cooling fluid so that the beverage, upon reaching the point of delivery, is also brought to the desired serving temperature. Such means comprise a refrigerating machine of the compressor-condenser-expander type, in which a volatile refrigerant, such as sulphur dioxide or methyl chloride, is circulated through a compressor, condenser, and expander and then back to the compressor, with which machine is combined a beverage dispensing system including a liquid reservoir disposed at a low point and a dispensing line in heat exchange relationship with the expander. The refrigerating machine is further utilized to apply compressed air or other motivating fluid to the beverage in the containing tank disposed at a low point, so that, as refrigeration proceeds with the withdrawal of the beverage, pressure is concurrently created and applied to force the beverage through the system.

The various principles, objects, and advantages of the invention will be made more apparent from the following description of a specific embodiment, illustrated in the accompanying drawings, wherein:

Fig. 1 is a side elevation of the invention,

Fig. 2 is a plan view of the pressure apparatus, and,

Fig. 3 is an end view of the parts shown in Fig. 2.

The liquid cooling and dispensing apparatus includes a source or reservoir for the liquid to be dispensed, such as a barrel 10, to which is connected a liquid feed line or conduit 11 extending to a dispensing point such as a faucet 12, which may be assumed to be at a higher point than the barrel, so that pressure on the liquid is required to force the beverage through the conduit and to the faucet. At some suitable point between the barrel 10 and the faucet 12, the conduit 11 is formed into a coil 13 which is disposed in heat exchange relationship with a refrigerating coil 14, so that the beverage is cooled during its flow through the dispensing system. The coils 13 and 14, as illustrated in

Fig. 1, are in the form of internesting helices, but it will be understood that such formation is not essential to the practice of the invention, and that by reference to beverage and refrigerant coils, it is simply intended to describe a type of heat exchange apparatus, and not a specific form.

Liquid refrigerant is fed to the refrigerant coil 14 through a supply line 15, through an expansion valve 16, the operation of which may be controlled by a thermostat 17 which is in contact with a portion of the refrigerant return or suction line 18. The thermostatic expansion valve may be of any known type, whereby, in operation, refrigerant is admitted through the valve if the demands of the system increase, or is cut off from the coil if a sufficiently low temperature has been reached. The operation of the expansion valve in supplying regulated quantities of refrigerant in response to the demand is therefore approximately proportional to the amount of beverage flowing through liquid coil 13.

The beverage is forced through the dispensing lines from the barrel 10 by fluid pressure, such as compressed air, which is supplied to the top of the barrel through a pipe line 19, from a source hereinafter described. As will be hereafter pointed out, the air pressure on the barrel is held within fairly close limits, so that the rate of flow of beverage through the conduit 11 will be substantially the same for any given opening of the faucet 12. The barrel itself is, in furtherance of such purpose, made substantially air tight, so that the air pressure will not be unduly dissipated.

Referring now to the lower portion of Fig. 1, and to the remaining figures, there will now be described the means for supplying refrigerant to the refrigerant coil 14 and air pressure to the barrel 10. These means are advantageously mounted on a base frame 20, which may be of any desired shape or size to support the various elements and to provide a compact and readily installed assembly. An electric motor 21, which is utilized as a driving member, is adjustably mounted at one end of the frame 20, adjustability being effected through a screw 22. The shaft of the motor 21 is provided with two pulleys 23 and 24, for driving a refrigerant compressor and an air pump, hereinafter described, and a fan 25 is also mounted on the end of the shaft to circulate air through a refrigerant condenser. The refrigerant compressor 27 is mounted on the base 20 remote from the motor 21, and it is pro-

vided with a driving wheel 28 which is connected by a belt 29 to the motor pulley 23. The compressor 27, which is here illustrated as being of the reciprocating piston type, is provided with a discharge line 31 for conducting warm compressed refrigerant to a condenser 32 mounted on the base 20 with its several convolutions in front of the motor fan 25. The discharge end on the condenser 32 is connected, by means of a pipe line 33, to a refrigerant receiving tank 34, mounted under the base 20, as best shown in Figs. 1 and 3.

The receiver 34 is connected, by means of a pipe line 35 and a coupling 36, to the refrigerant coil supply line 15, and the compressor 27 is connected, on its intake side, to the refrigerant return or suction line 18. As the motor is operated to drive the compressor, refrigerant is compressed, transmitted to the condenser 32 for cooling and liquefaction, and delivered to the receiver 34 for storage and supply to the expander 14. Here the liquid refrigerant is vaporized to expand and absorb heat, and the spent vapors are withdrawn into the compressor through the suction line, for recompression and circulation anew.

Mounted on the base 20 intermediate the motor 21 and the compressor 27 is an air pump 41, herein shown as of the reciprocating piston type, which is driven from the motor pulley 24 through a belt 42 extending around the pump pulley 43. Air is withdrawn from the atmosphere through a suitable dust filter or dehydrator (not shown) for compression and delivery to a pipe line 44, connected to the discharge side of the air pump, which communicates with a storage tank or reservoir 45. Interposed between the discharge port of the air pump and the delivery line 44, (or, alternatively, disposed on the tank 45), is a relief valve 46, which may be adjusted, through a screw 47, to open at any predetermined pressure. By means of the relief valve, the available air pressure in the tank 45 may be held below any desired and predetermined value, and hence a constant air pressure for the dispensed beverage is practically assured. It is advantageous to include the relief valve, with a slightly oversized air pump, in lieu of using an air pump whose capacity is such as to deliver just the theoretical amount of compressed air, computed on the amount of liquid to be dispensed and the demands on the refrigerating system for cooling. What is desired is enough compressed air to feed the liquid under a substantially uniform head, so that a fair degree of correlation between amount of liquid dispensed and refrigerant expended may be obtained. In obtaining this result in practice, it has been found desirable to provide the air relief valve for the purposes just described.

Air escaping from either the pump 41 or the receiver 45 through the relief valve 46 may be utilized for aiding in the condensation of refrigerant. To this end, the discharge side of the valve 46 is connected to a pipe line 48, (shown in Figs. 1 and 2) which terminates in front of the convolutions of the condenser 32. Excess air escapes through a plurality of apertures 49 in the end of the pipe 48, to blow against and through the condenser, thereby increasing the cooling effect. While the pipe 48 is shown here as being a single pipe, it will be obvious that a number of parallel pipes may be used, depending on the quantity of air available and the amount of cooling desired by this means.

The compressed air in the tank 45 is with-

drawn through a pipe line 51, provided with a shut-off valve 52, through a flexible conduit 53, to the pipe 19 which enters the space above the beverage in the reservoir 10. If desired, a filter 54 may be interposed in the pipe 53, to block the passage of moisture, oil, or residual dust that may be in the compressed air. It has been found that with a dust filter interposed at some point in the air path, as, for example, at the intake side of the air pump 41, the tank 45 itself may be relied upon as a means for separating moisture or oil from the compressed air. To this end, it will be observed from the drawings that the tank 45 is made of appreciable size, and the inlet and outlet lines are spaced from each other. Any atmospheric moisture which may condense due to the compression, or any drops of oil picked up by the air in its passage through the pump 41, will therefore have an opportunity to deposit in the tank 45. It has been found that the separated material collecting in the tank 45 is of slight bulk, compared with the tank capacity, and no special means appear to be required to remove the deposits, other than a suitable drain valve, which may be included as desired. Other forms of separators and filters may, of course, be employed in lieu of the simple tank shown in the drawings.

The operation of the refrigerant compressor 27 and the air pump 41 are both made dependent upon the refrigerating demand, by provided control instrumentalities for the motor 21 affected by the condition of the refrigerant in the expander 14. The electric motor is supplied with electricity through a pair of conductors 61 leading to a controller switch box 62, in which are disposed suitable electromagnetic devices constituting a switch for opening and closing the motor circuit. Current passes to the motor through an electrical conductor 63 when the control switch 62 is closed. As the current may be quite heavy, depending upon the size of motor used in the system, it is desirable to provide a remote control for the switch 62. Such control is obtained by shunting a portion of the main line current through a suitable resistance to a second electromagnetic switch, indicated at 65, which is automatically operated by the pressure (or temperature) in the refrigerant suction line. The wires for conducting current to the switch 65 may be encased in a conduit 66.

The construction of the switch 65 is such that, under the influence of refrigerant suction pressure, an electric circuit is closed or opened, which circuit, in turn, governs the flow of current through the electromagnet in the switch 62, controlling the main line circuit. Control switches of this type are well known, and hence detailed description of the structural and electrical features thereof are deemed unnecessary here. It may be noted, however, that the suction line 18 communicates through the compressor intake with a pipe line 67, whereby refrigerant pressure is applied to the switch 65. As this pressure increases, due, for example, to demands of cooling in the expander 14, which causes vaporization, the switch 65 is closed, to close the switch 62, and hence the main line circuit to the motor 21. When the motor is operated, both the compressor 27 and the air pump 41 are brought into play.

Operation of the compressor 27 causes the withdrawal, through the suction line 18, of spent vapor in the expander 14, and when the pressure drops to a desired value, the switch 65 is automatically opened, to open the motor circuit and discontinue

the operation. While the compressor is operating, the pump 41 is also in use to compress air for the beverage in the tank 10, thereby replenishing the supply used up in forcing liquid through the 5 coil 13, or aiding in cooling refrigerant in the condenser 32. As beverage flows from the barrel 10 under the pressure of the air, heat is absorbed by refrigerant in the coil 14, and the expansion valve 16 is opened or closed in response to the 10 demand for sufficient refrigerant to cool the beverage to the desired temperature. Accordingly, a system is provided for simultaneously cooling and dispensing beverages or other liquids, in which the several parts are so interrelated as to 15 achieve the desired result with a high degree of effectiveness.

It will be apparent to those skilled in the art that the various elements of the system such as the compressor, pump, switches, and the like, may 20 be of well known types, and that the parts as herein shown are subject to various rearrangements or changes. I also desire to point out that I do not claim as my invention these separate elements, but what I do claim is the system for 25 cooling and dispensing liquids, as set forth in the following claims.

I claim:

1. The combination with a beverage cooling and dispensing system including a refrigerant expander and a beverage coil in heat exchange relationship therewith, a source of beverage disposed at a lower point than the said coils, and a conduit for leading beverage from said source to said beverage coil, of means for supplying refrigerating 30 fluid to said refrigerant expander and fluid pressure to said beverage source, said means comprising a compressor for refrigerant, a conduit extending from the compressor to said expander, a motor for driving said compressor, means responsive to the condition of refrigerant in said refrigerant expander for operating said motor and thereby controlling the delivery of refrigerant to said expander, an air pump, a conduit leading from the discharge side of said air pump to said 40 beverage source to apply fluid pressure to beverage contained therein, and a driving connection between said motor and said air pump, whereby the operation of the air pump is governed by the thermal condition in said refrigerant coil.
2. In combination in a beverage cooling and dispensing system, a beverage reservoir, a conduit extending from said reservoir to a higher point for delivery of said beverage, an air pump, a conduit extending from the discharge side of said 45 pump to said reservoir to apply fluid pressure to said beverage to cause the upward flow thereof, a refrigerant compressor, a refrigerant expander in heat exchange relationship with said beverage delivery conduit, whereby beverage flowing through said conduit is cooled before delivery, electrically operated means for driving the pump and compressor, an electric circuit for supplying electrical energy to said means, a thermostatic switch for opening and closing said circuit, and means affected by the thermal condition of the refrigerant adjacent said expander for controlling said switch, whereby the operation of said pump and compressor are jointly governed by the 50 thermal condition of said refrigerant.
3. In combination in a beverage cooling and dispensing system, a beverage reservoir, a conduit extending from said reservoir to a higher point for delivery of said beverage, an air pump, a conduit extending from the discharge side of said 55

pump to said reservoir to apply fluid pressure to said beverage to cause the flow thereof, a refrigerant compressor, a refrigerant expander in communication with the discharge side of said compressor disposed in heat exchange relationship with said beverage conduit, a common drive means for said pump and compressor, means responsive to the thermal condition of said expander for controlling the operation of said drive means, and a pressure relief valve in said conduit from said pump to said reservoir, whereby the pressure on said beverage is maintained substantially constant.

4. In combination in a beverage cooling and dispensing system, a beverage reservoir, a conduit extending from said reservoir to a higher point for delivery of said beverage, an air pump, an air reservoir in communication with the discharge side of said air pump, a conduit extending from said air reservoir to said beverage reservoir, a pressure relief valve connected to said air reservoir to maintain the air therein below a predetermined pressure, a refrigerant compressor, a refrigerant expander in heat exchange relationship with said beverage delivery conduit and in communication with said compressor, a common drive means for said compressor and said air pump, and means responsive to the thermal conditions in said expander for controlling said drive means.

5. In combination in a beverage cooling and dispensing system, a beverage reservoir, a conduit extending from said reservoir to a higher point for delivery of said beverage, an air pump, an air reservoir, an inlet conduit extending from the discharge side of said pump to said air reservoir, a conduit extending from a point in said air reservoir remote from said inlet conduit to said beverage reservoir, a filter interposed in the air path leading through the intake side of the pump, said conduits and reservoir, said air reservoir and filter providing means for separating impurities from the air, a refrigerant compressor, a refrigerant expander in communication with the discharge side of said compressor, said expander being in heat exchange relationship with said beverage delivery conduit, common drive means for said pump and compressor, and means responsive to the thermal condition of said expander for controlling the operation of said drive means.

6. In combination in a beverage cooling and dispensing system, a beverage reservoir, a conduit extending from said reservoir to a higher point for delivery of said beverage, an air pump, a conduit extending from the discharge side of said pump to said beverage reservoir to apply fluid pressure to the beverage, a refrigerant compressor, a refrigerant condenser, said condenser being in fluid communication with the discharge side of said compressor, a refrigerant expander in heat exchange relationship with said beverage delivery conduit, said expander being in fluid communication with said condenser, a common drive means for the air pump and the compressor, a pressure relief valve in said air discharge conduit, and a pipe line extending from the discharge side of said pressure relief valve to said condenser, said pipe line being open at its end adjacent the condenser to direct relieved air through said condenser to cool the refrigerant.

7. In a liquid cooling and dispensing system including a liquid conduit and a cooling unit therefor, a refrigerant circuit for the cooling unit including a compressor and an air cooled condenser, an air pump, a pressure tank supplied thereby and communicating with said conduit, a pres-

sure relief valve communicating with said tank and adapted to vent air to the atmosphere when a predetermined pressure is attained therein, means for directing the vented air through the condenser, and a common drive means for both said compressor and pump.

8. In a liquid cooling and dispensing system including a liquid conduit and a cooling unit therefor, a base, a refrigerant compressor and an air pump mounted on said base, a motor for driving both compressor and pump mounted on

said base, an air cooled condenser mounted on the base, a refrigerant circuit for the cooling unit including the refrigerant compressor and condenser, a pressure tank mounted on the base and communicating with said pump and said liquid conduit, a pressure relief valve communicating with said tank and adapted to vent air to the atmosphere when a predetermined pressure is attained therein, and means for directing the vented air through said condenser.
